(57) **CLAIM**

The ornamental design for a module applied to a lighting assembly, as shown and described.

DESCRIPTION

FIG. 1 is a front right perspective view of our design for a module applied to a lighting assembly; and,
FIG. 2 is a front, plan view of our design for a module applied to a lighting assembly.

The portions or features of the module applied to a lighting assembly not shown in the drawings form no part of the claimed design. The dash-dash broken lines in the drawings are for the purpose of illustrating environmental subject matter and portions of the module applied to a lighting assembly that form no part of the claimed design. The dash-dot broken lines are for the purpose of illustrating a boundary and forms no part of the claimed design.
